UNITED STATES PATENT OFFICE.

GUSTAF SAUVOLA, OF ASTORIA, OREGON.

AERIAL RAILWAY.

Application filed September 8, 1922. Serial No. 586,921.

To all whom it may concern:

Be it known that I, GUSTAF SAUVOLA, a citizen of the United States, residing at Astoria, in the county of Clatsop and State of Oregon, have invented certain new and useful Improvements in Aerial Railways, of which the following is a specification.

My invention relates to improvements in elevated or aerial railways.

10 An object of my invention is to provide an aerial railway, whereby an automobile may be adapted to run on a cable or other suitable elevated track, whereby it is propelled by its own power.

15 A further object of my invention is to provide an aerial railway, which is applicable to either an automobile or an electric car, said aerial railway being provided with suitable trolley wires whereby an electric 20 vehicle will be supplied with current to propel the same.

A still further object of my invention is to provide an aerial railway, in which an ordinary automobile may be provided with 25 apparatus used in connection with my invention, in such a manner that it may efficiently be used as an aerial conveyance.

A still further object of my invention is to provide an aerial railway, wherein a complete 30 system of aerial transportation may be had, including cross overs and turn tables.

A still further object of my invention is to provide an aerial railway that is provided with suitable loading and unloading junctions at intervals along the line.

A still further object of my invention is to provide an aerial railway, that can be used to advantage in crowded cities, or in crossing bodies of water or rough country, 40 that is out of the way of ordinary traffic.

A still further object of my invention is to provide an aerial railway, that is extremely efficient in its operation and that is so constructed as to sustain the usage to 45 which it is adapted to be put, and that is comparatively simple and inexpensive in construction and that is well adapted for the purpose for which it is designed.

Other objects and advantages of the invention will become apparent during the course of the following description.

In the drawings, wherein like numerals are employed to designate like parts throughout the same,

55 Figure 1 is a side elevation illustrating

the method of adapting an ordinary automobile, to be run upon a cable,

Figure 2 is a rear elevation of the same,

Figure 3 is a detail view of the means whereby the power is derived from the rear 60 wheels of the automobile, to propel the same along a cable or track,

Figure 4 is a top plan view of a track cross section, used in conjunction with my invention,

Figure 5 is a central vertical section taken through a turn table, which is used in my aerial system,

Figure 6 is a perspective view of the interior thereof,

Figure 7 is a view illustrating a form of turn table, and a loading system used with my system, and

Figure 8 is a detail view of a post showing means thereon for supporting guy wires.

In the drawings, wherein for the purpose of illustration is shown a preferred embodiment of my invention, the numeral 10 designates any form of automobile body having the rear wheels 11 and the front wheels 12. 80 Mounted on the rear wheels 11 is a plate 13 which is held in place by suitable bolts or hooks 15 passed through the opening 14 in the plate 13. The plate 13 is provided with a shaft 16 having a reduced end 17, said portion 16 having a sprocket wheel 18 made integral therewith.

Mounted on the reduced portion 17 of the shaft 16 is a vertical frame member 19 which is prevented from slipping off of the reduced 90 portion 17 by means of a cotter pin or the like 20. The reduced portion of the shaft 16 is adapted to rotate in the lower end of the upstanding frame member 19 in a journal 21.

An upright frame member 22 having a journal 23 is mounted on the right hand shaft 16 on the reduced end 17 thereof and extends a substantial distance above the top of the automobile 10. Journaled between the upright frame members 19 and 22, a substantial distance above the top of the automobile body 10, is a longitudinal shaft 24, being journaled by means of the journals 25 and 26 respectively in the frame members 19 and 22. Cotter pins or the like 100 27 are provided to hold the shaft in place.

Mounted directly above the sprocket wheels 18 on the shaft 16, are sprocket wheels 28 which are carried by the shaft 24, and a sprocket chain 29 is adapted to connect each 110

pair of the sprocket wheels 18 and 28. It will thus be seen that by the rotation of the rear wheels 11, the sprocket wheels 18 will be caused to rotate in view of the fact that 5 the plate 13 which carries the sprocket wheels 18 is rigidly connected to said rear wheels, said sprocket wheels 18 causing the sprocket chains 29 to operate, thereby rotating the sprocket wheels 28 which are keyed to the shaft 24, thereby rotating the same. 10

In Fig. 2 of the drawings, it will be seen that the right hand vertical frame member 19 is bent at right angles, slightly above the sprocket wheels 28, said member 19 running horizontally for a substantial distance and again bent at right angles so as to resume a vertical direction and bent over as is clearly shown in the drawings to form a U-shaped frame. The sides of the U-shaped 15 frame 30 and 31 respectively are adapted to receive a shaft 32, on which is mounted a sprocket wheel 33, and a wheel 34 similar to a pulley wheel. Mounted directly below the sprocket wheel 33 on the shaft 24 is a sprocket wheel 35 over which as adapted 20 to run a sprocket chain 36 to the sprocket wheel 33. The wheel 34 is adapted to be mounted upon a suitable cable or other form of track 37.

30 The right hand vertical frame member 22 terminates a short distance above the shaft 37. A similar frame structure is carried by the front wheels 12 of the automobile 10 except that there are not sprocket 35 wheels or sprocket chains, but simply the plate 13 which is carried by the front wheels 12, which carries a shaft 17' which is journaled to the vertical frame member 22' on the right hand drive of the machine, and 40 a similar structure, that is the U-shaped frame 30' and 31' which carries a similar wheel 34' which is also adapted to run on the cable or track 37. As is clearly shown in Fig. 1 the longitudinal cross member 38 is mounted on the shafts 27 and 27' said member being provided with depending hooks 39 near each end thereof adapted to engage the end of a coil spring 40, the other end of which is connected to outstanding hooks 41. It will thus be seen that 45 the springs 40 will have a tendency to maintain the upright frame members 22 and 22' in a vertical position at all times.

It will thus be seen that an automobile 55 or like vehicle such as clearly illustrated in the drawings, may be used as an aerial railway. The power used is derived from the ordinary engine of such vehicles, said engine being connected to the rear wheels 11 by the ordinary drive shaft and other mechanism, said rear wheels 11, being the driving wheels. I have devised means whereby a plate similar to the one 13 is clamped to the rear wheels of the automobile, said plate 60 being provided with a sprocket wheel 18

over which runs a sprocket chain 29. It has been found that the form of frame which I have illustrated is entirely satisfactory for supporting the vehicle 10 in mid-air on the cable 37, but the same may be 70 changed if conditions warrant it. It will be seen that the sprocket chain 29 will rotate the sprocket wheel 28 which is carried by the shaft 24 which is journaled between the vertical members 19 and 22 respectively. 75 The rotation of the sprocket wheel 28 will rotate the shaft 24 which carries a similar sprocket wheel 35 over which runs a sprocket chain 36 to a sprocket wheel 33 on the shaft 32 which is journaled between the arms of the U-shaped member 30. The rotation of the sprocket wheel 33 rotates the shaft 32 on which is keyed a suitable wheel member 34 which propels the frame carrying the vehicle along the cable or other suitable track 37. It is to be understood 80 that I do not restrict myself to the form of track which should be used, and the cable 37 as is shown is merely illustrative of a form which may be used. 85

In order that my invention may be put to commercial use and advantage I have provided means whereby an entire system may be had wherein the cars may be switched from one direction to the other, or two lines may intersect without causing any difficulty. In other words I have made it possible to have a complete aerial railway in which traffic may be dispatched in various directions with ease. Fig. 4 of the drawings clearly illustrates a form of intersection, or track cross which may be used to advantage in accordance with my invention. The numeral 42 designates posts which are spaced the desired distance apart, as is deemed advisable. Mounted on the posts 42 are collars 43 which are provided with the hooks 44 to which are connected the guy wires 45. The collars 43 may be secured to the posts 42 in any desired manner, and I have illustrated a form which may be used, namely a flange 46 which is carried by the post 42 for the collar 43 to bear upon. Insulator hangers 47 provided with the arms 48 are supported by means of wires 50 which are secured to said arms by means of bolts or other suitable means 49. The diagonal guy wires 50 are supported at their opposite ends by means of hooks 44 on the collars 43. The hangers 47 are also provided with the arms 51 which are fastened to the guy wires 45 by means of suitable clips 52, thereby insuring a strong connection for the cross overs, 100 that is capable of sustaining the necessary load that is required to be held. It will thus be seen that a very simple form of track intersection has been made that will permit the system to be provided with main lines and cross lines without any difficulty. 105 110 115 120 125 130

In this way an entire city may be equipped with an aerial railway, that will be even more efficient than the form of conveyances now commonly in use, as there will be no heavy traffic for the conveyances to become mixed in, thereby causing delay in transportation, or at any rate accidents.

In addition to the form of track intersection, I have devised what may be termed a turn table, to direct the vehicle in various directions when it is desired, that is, the turntable may be installed at various intervals along the line to switch a vehicle, and one may be used at the starting junction to advantage. An annular housing or frame 53 is supported by means of brackets 54 and 55. The bracket 55 is provided with depending arms 56, which will more fully be discussed below. The bracket 55 is provided with a vertical shaft 57, which is provided near its lower end with a beveled gear 58. The numeral 59 designates a longitudinal shaft, that is provided with a small beveled gear that is adapted to mesh with the large beveled gear 58 on the shaft 57. The opposite end of the shaft 59 is provided with a wheel 61 which is adapted to run around the upper edge of the housing 53. Mounted within the housing 53 are the cross members 62, which are carried by the shafts 59 by means of suitable supporting clips 63. As is clearly shown in the drawings, the cross sections 62 are provided with cut out portions 64, to allow for the frame of the vehicle to pass therebetween. The bottom of the cross sections 62 are provided with track members 65 on both sides thereof as is clearly shown in Fig. 5 of the drawings. The numeral 66 designates pivoted track sections which are secured near the inner end of the track portions 65 by means of suitable bolts or other pivoting means 67. The pivoted track sections 66 are normally held in a vertical position by means of a suitable spring 68, and it will be seen that when the wheel 34 strikes the section, it will pull it down into horizontal position, thereby spanning the opening 64 and allowing the wheels to pass on. As soon as the wheel 34 passes over the end of the pivoted section 66 the spring 68 will raise it again to a vertical position, so that it will be out of the way if it is desired to swing any of the other pivoted track sections 66 down into an operative position.

It is to be noted in Fig. 6 of the drawings, that the depending arms 56 of the bracket 55 are fastened to the cross vane 62 so as to give additional strength. Wings 69 are mounted on the annular housing 53 adjacent the openings 70 in said housing, which are adapted to register with the openings 64 formed in the cross sections 62. The wings are also provided with track sections 71 and a pivoted track section 72 similar to the

pivoted track section 66. The tracks 73 are adapted to be connected to the track sections 71 of the wings 69. As is clearly shown in Fig. 7 of the drawings, the tracks 73 may be inclined toward the ground, thereby allowing the vehicle to be run down to the ground to discharge passengers or to take on the same, or for repairs when it is necessary. As is shown in Fig. 7, the track 73 may be mounted on a post 74.

It is of course necessary to provide means whereby the cross members 62 may be rotated within the casing 53, and I have devised means whereby it can be done mechanically or electrically. In Fig. 5 of the drawings on the left hand side I have illustrated an electric motor which may be used to rotate the cross members 62. A pulley wheel 75 is mounted on the shaft 59 and over which is adapted to be run a pulley belt 76 which is operated by the pulley 77 of the motor 78. It will thus be seen that when the motor 78 is run the pulley 75 by reason of the pulley belt 76 will be rotated thereby rotating the shaft 59 which will rotate the pinion 60 which meshes with the large gear 58. It is of course to be understood that the gear 58 is stationary and thereby allowing the pinion 60 to rotate around the same, carrying with it the shaft 59 and the wheel 61 which will run along the top edge of the housing 53. If it is not convenient to have electricity, a starting wheel 79 may be mounted on the shaft 59 as clearly shown on the right hand side of the drawings in Fig. 5, and a long sprocket chain 80 adapted to run thereover, in such a manner that when the sprocket chain is moved the sprocket wheel 79 will move likewise causing the wheel 61 to ride around the top of the housing 53.

It is of course to be understood that street cars, that are adapted to be used on an aerial cable, may be used in accordance with my invention equally as well as an automobile as illustrated, and to this end, I have provided a trolley wire 81, which is adapted to contact with the ordinary trolley wheel of a street car. Of course, the trolley wire 81 would have to be broken at 82, to allow for the cross section 62 to rotate within the housing 63.

In the operation of an aerial system as I have fully described, an automobile may be equipped with an apparatus as is clearly shown in the drawings. With such a construction the vehicle may be propelled on a cable or other track 37 by its own power, that is the power that is ordinarily used in such conveyances when it runs on the ground. In other words, a plate similar to the plate 13 as shown in Fig. 3 of the drawings is clamped on the rear wheels 11 by means of suitable bolts or hooks 13. A sprocket wheel 18 is made integral there-

115

120

125

130

with and thereby the rotation of the wheels 11 which carry the plate 13 will rotate the sprocket wheel 18. It will of course be seen that it is not necessary to use sprocket 5 wheels or chains, as a form of pitman could be used equally as satisfactorily, but I will explain the form wherein sprocket wheels and sprocket chains are used. The sprocket wheel 18 is adapted to rotate the sprocket 10 chain 29 which runs over the sprocket wheel 28 which is carried by the shaft 24, which is journaled between the vertical frame members 19 and 22 which are carried by the shaft 17 which are carried by the plate 13. The rotation of the sprocket wheel 28 rotates the shaft 24 on which is carried a sprocket wheel 35 which operates a sprocket chain 36 which runs over a similar sprocket wheel 33 which is carried by the shaft 32, 20 which is mounted between the arms 31 and 30 of the U-shaped frame member, which is carried by the upright member 19. It will thus be seen that the wheel 34 which is keyed to the shaft 32 will be rotated, 25 thereby propelling the vehicle along the cable or other form of track 36. As shown in Figs. 4 and 8 of the drawings, I have clearly illustrated a form of track intersection which may be used, the operation of 30 which is clearly understood from the foregoing description.

As is clearly shown in Fig. 7 of the drawings, an efficient method is devised whereby the bodies or vehicles 10 may be lowered so as to discharge or take on passengers or the like. It will clearly be seen that the track 73 is an inclined track leading from the wing 69 which is carried by the housing 53 of the turn table structure. 40 The track 73 is connected at its other end to a comparatively short post 74, some distance away from said turn table structure. There may be as many tracks 73 as is deemed advisable, and of course in a large system 45 of aerial transportation it would be necessary to have a great many such tracks as is clearly shown in Fig. 7, but the explanation of one will suffice for the others. We will now assume that there is a vehicle such as 50 is illustrated by the numeral 10 in Fig. 1 of the drawings, located on the lower end of the inclined track 73. This vehicle is propelled up the inclined track 73 onto the track portion 71 which is carried by the 55 wing 69 of the housing 53 of the turn table structure. Of course, if it is desired to run the conveyance on to the track 73 and not to change the course of the conveyance, it is not necessary that the conveyance be 60 stopped and run on to the turn table mechanism. However, assuming that it is desired to turn the automobile in the opposite direction to which it is now pointed. It is of course to be understood that we are now 65 discussing the left hand wing 69. After the

conveyance has run up the track section 73 onto the track 71 and is kept moving it will strike the vertical track section 72 causing it to fall down and close the gap and allow the car to pass onto the track 65 of 70 the cross sections 62 within the casing 63. It will also strike the pivoted track section 66, which is pivoted to one section 65 causing it to swing down and rest on the opposite track section 55. The conveyance can 75 now be stopped, and by operating the sprocket chain 80 over the sprocket wheel 79 the cross section 62 can be made to turn by reason of the wheel 61 running around the upper edge of the annular casing 53 80 which is caused by means of the sprocket wheel 79 keyed to the shaft 59 which is provided with the beveled gear 60 at its opposite end. The beveled gear 60 meshes with the stationary beveled gear 85 58 which acts as a support for the cross section 62. The cross section 62 may be rotated as far as is desired, and the conveyance may be switched back onto any of the 90 outgoing tracks with very little difficulty. This, instead of having an automobile as shown in the drawings, a street car is used, it is necessary to provide a trolley wire 81 which is clearly shown in Fig. 5 of the drawings as being broken at 82 to allow the 95 same to be carried by the cross section 62 when the same is rotated. In the event it is possible to have electricity the cross section 62 may be rotated by means of a motor 100 78 which operates the pulley belt 76 over the pulley wheel 75 which is keyed to the shaft 59. By the use of this turn table structure, a conveyance may be dispatched in various directions thereby forming a more 105 satisfactory system, than if such a turn table were not in use. It is of course to be understood, that the turn table structures may be placed at intervals along the system to advantage, and that any form of track may be used, such as a cable 87, or 110 if it is deemed advisable, various other forms of track sections. It may be deemed advisable to use a form of rack bar and pinion, especially on the inclined track 73.

It is to be understood that the form of my invention herewith shown and described is to be taken as the preferred embodiment of the same, and that various changes in the shape, size and arrangement of parts may be resorted to without departing from the spirit of my invention or the scope of the subjoined claims.

Having thus fully described my invention what I claim is:—

1. In combination with an elevated rail-way, an annular housing, a rotatable turn table mounted within said annular housing, said turn table member comprising two intersecting sections, said intersecting sections being provided with cut out portions at 125 130

their intersections, and pivoted track sections carried by the lower end of said cross sections.

2. In combination with an elevated railway, a turn table comprising an annular housing, cross turn table sections mounted within said annular housing, wings carried on the outside of said annular housing, openings in said wings, and pivoted track sections adapted to be normally held in a vertical position.

3. In combination with an elevated railway, a turn table comprising an annular housing, cross turn table sections mounted within said annular housing, said cross sections being provided with cut out portions near the lower end thereof, pivoted track sections mounted in close proximity to said cut out portions and adapted to be swung down to span said cut out portions, track

sections carried by the lower end of said cross sections, means carried on the outside of said annular housing, cut out portions being provided in said annular housing in close proximity to said wings, and means to rotate said cross turn table sections.

4. In combination with an elevated railway, a turn table comprising an annular housing, a cross turn table member mounted within said annular housing, means to rotate said cross turn table section, and an inclined track carried by said annular housing.

In testimony whereof I affix my signature in presence of two witnesses.

GUSTAF SAUVOLA.
